UNITED STATES PATENT OFFICE.

EDWARD P. COLE, OF CHICAGO, ILLINOIS, ASSIGNEE TO COLE MANUFACTURING COMPANY, OF CHICAGO, ILLINOIS, A CORPORATION.

CAR HEATER.

Application filed March 12, 1920. Serial No. 365,254.

To all whom it may concern:

Be it known that I, EDWARD P. COLE, a citizen of the United States, and a resident of Chicago, county of Cook, and State of Illinois, have invented certain new and useful Improvements in Car Heaters, of which the following is a specification.

My invention has reference more particularly to a heater of the type which is usually made in a portable form and used in freight cars or other compartments containing materials such as fruits and vegetables, to maintain a temperature in the car or compartment, during cold weather, which will prevent freezing or damage to the contents of the car or compartment.

These heaters are used particularly in cars during transportation, and therefore necessitate a construction which will contain an ample supply of fuel and automatically feed same onto a grate or into a fire-box so as to furnish heat continuously during the period of transportation, without attention, and such heaters have suitable provision for draught which will effect free combustion of the fuel and regulate the heat so that the heating is uniform during the time that the heater is in operation.

The principal objects of my invention are to provide an improved heater of this character having the necessary requirements as to storage capacity and regulation of combustion, and in which the contents are securely confined to prevent escape of ignited or burning particles of fuel therefrom; to provide a larger opening from the fuel magazine to the combustion chamber than heretofore employed in heaters of this character; to provide a special form of valve for closing such larger opening, wherein the valve is arranged to occupy a restricted space within the heater when in the open position; to provide an improved arrangement of draft openings; to prevent excessive pre-heating of the fuel before it is deposited into the combustion chamber; to provide a heater which may be conveniently taken apart and assembled and in which the removable parts are securely locked in the proper position when the heater is assembled; and in general to provide an improved car heater of this character which is economical to manufacture, more reliable, and safer to use than those heretofore constructed.

On the drawings, Fig. 1 is a vertical sectional view of a car heater embodying my improvements; Fig. 2, a transverse sectional view on the line 2—2 of Fig 1; Fig. 3, a top view of the valve housing with the top plate removed and showing the valves in the closed position; Fig. 4, a sectional view through valves and valve housing on the line 4—4 of Fig. 1; Fig. 5, a sectional view on the line 5—5 of Fig. 1 showing the door opening and the door, and Fig. 6, a fragmentary top view of the heater showing the manner of attaching the cover for closing the inlet to the fuel magazine.

Referring to the drawings, the reference numeral 1 indicates the outer shell or casing of the heater which is cylindrical in form and may be circumferentially corrugated for a portion of its length, as shown, if desired, and has a top 2 secured to and closing one end thereof. The other or lower end of the casing 1 is reinforced by an angle iron 3 which extends around and is secured to the edge thereof by rivets 4, and this angle iron has one flange extending outwardly under the edge of the casing 1, as shown in Fig. 1.

The upper portion of the casing serves as a magazine for fuel and has a ring 5 riveted or otherwise secured to the inside of the casing wall 1, near the bottom of the magazine, said ring being bent inwardly at the lower end as indicated at 6, to afford a taper fit with the upper end of a hopper 7 which is mounted directly therebelow.

This hopper tapers downwardly to a central opening, and projects into the upper end of a cylindrical shell 8, said shell being of less diameter than the casing 1 so as to provide an annular exhaust passageway 10 therebetween. At the base of the hopper, and somewhat above the lower end of the shell 8, is a partition consisting of the valve housing 11—12 and a split heat insulating ring 13, composed of spaced plates with insulating material such as asbestos interposed therebetween. The plates 11 and 12 of the valve housing are secured together to form a valve slideway therebetween and the former at its inner end has a large opening therethrough surrounded by a horizontal flange 15 to which the split ring 13 is secured, and an upright flange 16 to which the lower end of the hopper 7 is secured so as to discharge through the opening 14.

which latter is adapted to be controlled by the sectional valve 17-18 mounted in the slideway between the plates 11 and 12. The plates 11 and 12 are secured to the wall of the shell 8 in any convenient manner as by riveting or bolting a flange 19 of the upper plate 11 to the shell wall, and the partition 13 is held in place in the shell by having the periphery thereof engaged in a circumferential groove on the inside of the shell, formed by corrugating the shell wall at 20. This construction just described forms an insulating space or chamber 21 around the hopper 7 which together with the insulating partition 13 serves to prevent excessive pre-heating of the fuel in the hopper by the heat of the combustion chamber below the partition 13, the chamber being ventilated by vertically spaced rows of perforations 22 and 23 in the wall of the shell 8.

It will be observed that the width or diameter of the opening 14 is somewhat greater than the distance from the periphery of said opening to the casing wall 1 and as it is desired to employ a valve which entirely opens or closes the outlet 14 and at the same time contain the valve within the casing 1 when in the open position, I have provided the sectional valve 17-18 above mentioned. The plates 11 and 12 are, of course, wide enough to accommodate valve sections of sufficient width to entirely cover the opening 14 and each has a spacing flange 24 at each side which separates the plates sufficiently to permit freedom of movement of the valve sections. The lower plate 12, over which the lower valve section 18 slides, is cut away below the opening 14, as indicated at 32 in Fig. 3, and has extensions 25 at each side of the opening with guide flanges 26 thereon engaging under the lateral edges of the section 18 to support same when moved to the closed position. The inner end of this section 18 may be rounded, as indicated at 27, if desired, and has the edge tapered to facilitate closing. The outer end of said section is curved, as indicated at 28, to conform to the curvature of the casing wall 1 and thus enable the valve section to be fully withdrawn, and has a depending lug 29 extending outwardly and bifurcated to receive the end of a handle 30 which is secured to the bifurcated extremity of the lug 29 by a pivot pin 31. The plate 12 is formed with a central groove or recess 33 extending in the direction of movement of the valve, to accommodate the lug 29 and also the handle 30 when the valve is closed.

The upper valve section 17 is supported on the lower section 18 and is interlocked therewith by means of a lost motion connection consisting of an upstanding lug 34 on the top of the section 18, adjacent the outer end, which engages in a longitudinal

channel 35 in the under face of the section 17. The section 17 is centrally arched to form this channel 35 and the plate 11 correspondingly arched to receive the arched portion of the section 17, and the channel 35 is closed at the inner and outer ends by end walls 36 and 37 respectively against which the lug 34 engages to effect operation of the upper valve section. The inner end of the valve section 17 may be straight, if desired, as indicated at 38 in Fig. 3, and the edge beveled to facilitate closing, and the outer end is convexly curved to conform to the curvature of the casing wall 1 and enable said section to be fully withdrawn from the opening 14.

The plate 11 of the valve housing has an outwardly extending lug 39 which projects through the wall of the casing, said wall being provided with an opening 40 for this purpose which is also sufficiently large to receive the valve lug 29 and handle 30 therethrough, and the lug 39 may be apertured as at 41 to receive a pin or other fastener to engage the end of the handle 30 and lock the valve in the closed position. The end of the handle is enlarged at 43 so that when the valve is closed, said enlarged portion fits close in the opening in the casing wall through which the handle is inserted.

A cylindrical shell 42 of suitable diameter to afford a fairly close sliding fit in the casing 1 is inserted in the lower end of the latter and has an inturned flange 41 around the upper end which seats against an annular internal corrugation 56 in the wall of the casing 1 and prevents admission of air to the exhaust passageway 10 from between the casings 1 and 42. This shell 42 has a tapered or hopper shaped wall 44 inserted in and secured to the upper end thereof and terminating in a large central opening, directly below the opening 14. A plurality of brackets 45 mounted on the exterior of the wall 44 have inwardly extending stems 46 on which a conical grate 47 is mounted, the latter being formed with slots or apertures 48 for ash deposit and draught circulation. The grate 47 is of less diameter than the opening at the lower end of the wall 44 and this leaves a space 49 therebetween which also serves to permit ash deposit and afford circulation, and the wall 44 has perforations 61 adjacent the lower end for the same purpose.

The lower end of the shell 42 is closed by an insulating partition which is spaced sufficiently below the grate 47 to leave ample room for ash deposit. This partition comprises an upper disc 50 having a down turned annular flange 51 which engages snugly within and is secured to the end of the shell 42. Spaced below the disc 50 and secured against the lower edge of the flange 51 is a partition 52 comprising a pair of

- spaced plates with interposed sheet of heat insulating material, such as asbestos. Secured to the disc 52 around the edge thereof is a plurality of legs 53 each of which 5 has an inturned angular portion 54 at the upper end secured to the disc 52 by rivets or in any other substantial manner, and an outturned portion 55 at the lower end which engages under the angle iron 3. The 10 intermediate upright portions of the legs 53 engage closely against the upright flange of the angle iron 3 and are secured to the casing wall by bolts 57 whereby the heater is securely locked in the assembled form. 15 These legs 53 hold the bottom 50—52 well above the lower end of the casing 1, so as to avoid communication of heat from the ash pit to the floor on which the heater is supported, such communication of heat 20 being further prevented by the provision of a large number of perforations 60 in the wall of the casing 1 below the partition 50—52 which thoroughly ventilate the space below said partition.
- 25 Air for effecting combustion is admitted to the ash chamber through openings 58 and 59 respectively in the walls 42 and 1 spaced well above the bottom of the ash chamber. The wall 1 is formed with an external annular corrugation 82 with the perforations 59 in the upper slope thereof and the perforations 58 in the wall 42 arranged near the bottom of the corrugation and preferably in horizontal staggered relation, so 30 as to permit free admission of air and at the same time prevent any possibility of sparks from the ash chamber reaching the exterior of the casing. Outlet from the combustion chamber for the combustion 35 gases is afforded by a plurality of perforations 62 in the shell 8 below the partition 13 which discharge into the passageway 10 between the shell 8 and casing wall 1, and openings 63 in the wall 1 at the upper end 40 of the annular passageway 8 lead to the exterior of the heater.
- 45 For affording access to the ash pit below the grate 47, the casing wall 1 and shell 42 are provided with matching openings 64 and 65 closed by a door 66 which is mounted in a frame 67 provided with flanges 68 at each side of the opening overlapping the edges of the door 66 so that the latter may slide vertically to open and close the inlet 50 to the ash chamber. The frame 67 is formed with a flange or abutment 69 at the bottom against which the door closes and the door has a handle 70 for operation thereof.
- 55 Access is had to the fuel magazine 71 through an opening 72 in the top wall 2 which is closed by a centrally depressed cover 73 having a flange 74, which overlaps the top 2 around the opening 72. A strap 75 has a depressed portion 76 adja-
- cent each end secured to the cover 73 so as to afford a raised intermediate portion 77 to serve as a handle, and the ends of this strap project beyond the periphery of the cover 73, as indicated at 78 so that they 70 may be engaged under oppositely extending plates 79 on the top 2 for locking the covering in the closed position.
- This heater is adapted to be set up on the car floor or suspended from the ceiling of the car and has chains 80 or any other suitable hangers secured to the top for attaching the heater in the car.
- It will be observed that the valve casing 11—12, hopper 7, shell 8 and associated parts are assembled in a unitary structure which is removable from the casing 1, and in assembling the heater, this valve section is inserted with the flange at the upper end of the hopper 7 engaged against the 80 tapered flange 6 of the ring 5 and with the lug 39 inserted through the aperture 40 of the casing wall 1. When inserting this valve section the valve is closed so that the handle 30 is pushed in and permits insertion of the lug 39 and outer end of the handle through the aperture 40. After the valve section has been mounted in the described position, the bottom section 42 is inserted in place with the door opening 65 85 thereof registering a door opening 64 of the casing wall 1 and removably secured in place by the bolts 57. In this position the wall 44 engages against the lower edge of the shell 8 and cooperates with the tapered flange 6 to center and hold the valve section in proper position in the casing 1, and the inturned upper edge 81 of the casing 42 engages the corrugation 56. By removing the bolts 57, the internal parts 90 of the heater, that is the hopper and valve section or unit and the combined fire-pot and ash-pit section or unit, can be readily removed for renewals and repairs.
- 95 With the valve structure shown herein, the handle 30 hangs downwardly when the valve is open and thereby holds the valve against accidental closing, the lower section 18 being directly held by the handle and the upper section 17 being held in the 100 open position by engagement of the end wall 37 of the channel 35 with the lug 34. To close the valve, the handle 30 is lifted to a horizontal position and pushed inwardly thereby sliding the valve section 18 alone, 105 inwardly until the lug 34 engages against the end wall 36 of the channel 35, whereupon the upper valve section 17 is moved inwardly with the valve section 18 until the opening 14 is entirely closed. In opening the valve, the outward movement of the handle 30 first draws the valve section 18 outwardly until the lug 34 engages against the wall 37, whereupon the valve section 110 115 120 125 130 135 are entirely withdrawn from the opening 14. By using a valve of this character, the opening 14 may be of large diameter and at the same time the valve controlling same 5 which, if a single valve, would necessarily extend outside the casing 1 in the open position, is contained entirely within the casing wall 1 in the open position.

While I have shown and described my 10 invention in a framed form, I am aware that various changes and modifications may be made therein without departing from the principles of my invention, the scope of which is to be determined by the appended claims.

I claim as my invention:

1. In a heater of the class described, the combination of a casing having a combustion chamber, a fuel magazine thereabove 20 with a bottom tapering to a discharge opening which leads into the upper end of the combustion chamber, a shell spaced from the wall of the casing and said tapered bottom and forming a draft passageway from the 25 combustion chamber separated from the tapered bottom by an air space, and a horizontal partition mounted in said shell adjacent the lower end of the tapered bottom, and separating the air space from the combustion chamber.

2. In a heater of the class described, the combination of a casing having a combustion chamber and a fuel magazine above and provided with a discharge spout leading 35 into the combustion chamber, a shell providing an annular draft passageway around and spaced from the spout, and a horizontal partition extending outwardly from the lower end of the spout to said 40 shell, the combustion chamber having draft outlet means below the partition and leading into the lower end of said draft passageway at a distance from the spout.

3. In a heater of the class described, the 45 combination of an upright casing having a combustion chamber at its lower end and a fuel magazine at its upper end provided with a hopper bottom leading into the combustion chamber, said casing having discharge outlets for the products of combustion adjacent the upper end of said hopper bottom and partition walls extending about 50 said hopper bottom and enclosing same from the lower to the upper end thereof so as to form an insulating air space therearound and cover the top of the combustion chamber and an annular draft passageway leading from the combustion chamber to 55 said discharge outlets.

60 4. In a heater of the class described, the combination with an upright casing having a combustion chamber at the bottom and a fuel magazine thereabove with a spout leading 65 into the combustion chamber, an annular draft passageway around and spaced

from the spout, a horizontal partition extending around the lower end of the spout and forming the top of the combustion chamber, draft outlets in the lateral walls of the combustion chamber below the partition leading from the upper end of the combustion chamber, to the draft passageway and a valve for controlling the supply of fuel from the fuel magazine to the combustion chamber.

5. A heater of the class described comprising an upright casing having a fuel magazine in its upper portion, an insulated bottom for said casing, a spout separable from the magazine and the insulated bottom 70 and forming the bottom of said fuel magazine and having a valve-controlled discharge opening, a grate intermediate said spout and said insulated bottom, means for holding said spout, grate and insulated bottom in spaced relation to provide a combustion chamber and ash-pit, and common fastening devices for removably securing said insulated bottom, grate, spout and spacing 75 means in position.

6. In a heater of the class described, the combination of an upright casing having a magazine at the top, and a removable casing telescoping within the bottom and providing an ash chamber and grate surface, a removable section between the magazine and said removable casing forming an annular draft passageway within the casing from the combustion chamber and having a partition forming the top of the combustion chamber and provided with a spout leading from the magazine through said partition, a valve for controlling the supply of fuel from the magazine to the combustion chamber and means for simultaneously locking the removable section and the removable casing in the upright casing.

7. In a heater of the class described, the combination of an upright casing having an internal ring spaced from its upper end, a lower section comprising a fire-pot and ash-pit removably secured at the lower end of said casing and a separate spout section forming a hopper bottom for said fuel magazine and removably held in position by said lower section with its upper edge in engagement with said ring.

8. In a heater of the class described, the combination of an upright casing having an internal ring spaced from its upper end, a lower section comprising a fire-pot and ash-pit removably secured at the lower end of said casing and a separate spout section forming a hopper bottom for said fuel magazine and removably held in position by said lower section with its upper edge in engagement with said ring, the latter and said lower section having conical surfaces for engaging and centering said hopper section.

9. In a heater of the class described, the combination of an upright, cylindrical casting having an internal ring spaced from its upper end and draft outlets adjacent and below said ring, a lower section comprising a fire-pot and ash-pit removably secured within the lower end of said casing, a shell above said lower section, a spout having a valve-controlled discharge opening, mounted on said shell and forming the hopper bottom of a fuel magazine in the upper portion of said casing, said spout and said shell being removably held in position by said lower section with the upper edge of said spout engaging said ring and with said shell spaced from the wall of said casing to provide an annular draft passage leading from the fire-pot to said draft outlets. 35
10. A heater of the class described comprising an upright outer casing having a fuel magazine in its upper portion, a lower section comprising a fire-pot and ash-pit removably secured within the lower end of said outer casing, and a spout section above said lower section and removably held in position thereby, said spout section comprising a hopper bottom for the fuel magazine having a valve-controlled discharge opening and walls spaced from said hopper bottom to insulate the same and provide an an- 40
5. nular draft passage leading from the fire-pot, said casing having an internal ring fitting snugly within the upper portion of said spout section and discharge outlets leading from the upper portion of said draft passage. 45
11. A heater of the class described comprising an upright, cylindrical, outer casing having a fuel magazine in its upper portion, said magazine being provided with a hopper bottom having a valve-controlled discharge opening, a cylindrical, combined fire-pot and ash-pit section snugly fitting within the lower end of said casing and removably secured thereto, said section having an insulated bottom above the lower edge of said outer casing and a fuel-supporting grate above said bottom and spaced from said hopper bottom to provide a combustion chamber, said section and said outer casing having staggered air inlets and registering door openings, and a door for closing said openings, said outer casing having draft outlets adjacent the upper portion of said hopper bottom and the latter having spaced 50 walls for insulating the same from the combustion chamber and for directing the products of combustion to said draft outlets. 55

EDWARD P. COLE.
